[57] ABSTRACT

The petunia cultivar 'Caschika' is particularly characterized by vigorous growth and continued flowering under hot summer conditions and in mild winters; a long garden season with flowering from early spring until late winter; prolific growth with vigorous green-gray (R.H.S. 137B) foliage and pink-lavender (R.H.S. 78A) flowers.

1 Drawing Sheet

2

6. The cultivar is not particularly susceptible to common petunia diseases.

Of the many commercial cultivars known to the inventor, the most similar in comparison to 'Caschika' is 'Charisma'. In comparison to 'Charisma', however, 'Caschika' has better garden performance due to its vigorous growth and distinctive flower color. Unlike 'Charisma', the cultivar 'Caschika' continues to flower during moderate winter conditions.

The accompanying photographic drawing shows typical flower and foliage characteristics of 'Caschika', with the color being as true as possible with illustrations of this type.

Sheet 1 is a side view of a typical specimen of the variety 'Caschika' showing the abundant flowering, distinctive flower color and plant shape.

In the following description, color references are made to The Royal Horticultural Society Colour Chart. The color values were determined between 10:00-12:00 a.m. on January, 1996 under full sunlight at Mishmar, Hashiva.

20 Classification:

Botanical.—Petunia hybrid.

Commercial.—Petunia cultivar.

'Caschika' plant:

Growth habit.—Prolific and fast growing.

Plant height.—8-10 inches.

Spreading area.—30 inches.

Blooming period.—Throughout year.

25 Stem:

Thickness.—2-3 mm.

Color.—Green (R.H.S. 137B).

Pubescence.—Yes.

Branching.—Free.

Length of internode.—10-20 mm.

30 Leaf:

Arrangement on stem.—Alternate.

Shape.—Ovate.

Size.—Length: 75 mm. Width: 50 mm.

Thickness.—0.2 mm.

Color.—Green-Gray (R.H.S. 137B).

Pubescence.—Yes.

The following traits have been repeatedly observed and are determined to be basic characteristics of 'Caschika' which in combination distinguish this petunia as a new and distinct cultivar:

1. Excellent garden performance under full sunlight and also suitable for indoor usage.

2. Good weather tolerance including vigorous growth and flowering under hot weather conditions and continued flowering through moderate winters.

3. Prolific growth with vigorous green-gray foliage. p 4. Numerous pink-lavender (R.H.S. 78A) flowers of medium size. The cultivar flowers early in the growing season.

40 5. Long garden season maintaining growth and flowering from early spring until late winter.

Plant 10,427

3

Flower:

Orientation at opening.—Upright.

Type.—Single.

Shape.—Regular and rounded with a united corolla that has 5 lobes and a long straight tube.

Diameter.—40–50 mm.

Color.—Upper surface: Pink-lavender (R.H.S. 78A). dark eye (R.H.S. 83B). Lower surface: Pink-lavender (R.H.S. 78A).

Peduncle.—Length: 15–20 mm. Color: Green (R.H.S. 137B).

4

Reproductive organs.—Pistil: Number: 1. Color: Green (R.H.S. 138C). Stamens: Number: 5. Anther: Gray-Blue (R.H.S. 96C). Filament: Green (R.H.S. 138D).

Disease resistance: The 'Caschika' is not particularly susceptible to common diseases of petunia.

I claim:

1. A new cultivar of petunia plant named 'Caschika' as herein shown and described.
